DESIGN FOR A CIGARETTE CONTAINER

James H. Horsley, Chicago, Ill., assignor to Shanklin Manufacturing Company, Chicago,
Ill., a corporation of Illinois

Application August 29, 1938, Serial No. 79,621

Term of patent 14 years

To all whom it may concern:

Be it known that I, James H. Horsley, a citizen of the United States and resident of Chicago, in the county of Cook and State of Illinois, have invented a new, original, and ornamental Design for a Cigarette Container, of which the following is a specification, reference being had to the accompanying drawing, forming a part thereof.

Fig. 1 is a front elevational view of a cigarette container showing my new design;

Fig. 2 is a top plan view of the same;
Fig. 3 is an end elevational view of the same;
Fig. 4 is an end elevational view of the same with the cigarette compartments in open position.

I claim:

The ornamental design for a cigarette container, substantially as shown.

JAMES H. HORSLEY.
